TIME RECORDER SYSTEM

Adolph L. Denniston, Park Ridge, Ill., assignor to
 Stromberg Electric Company, Chicago, Ill., a
 corporation of Delaware

Application September 24, 1932, Serial No. 634,666

7 Claims. (Cl. 58—24)

My invention relates to job time recorders and more specifically to a synchronous motor-driven job time recorder arranged to suspend operation during non-working periods.

5 The purpose of a job time recorder is to make a printed record of the time a workman starts and stops work on a given job. This printed record is used by the cost-keeping department as a basis for determining the labor cost involved in 10 manufacturing a given product.

The workman is provided with a card or ticket upon which he stamps the starting time by inserting the card in the job time recorder and manually actuating the imprint lever which 15 causes the recorder to make a time imprint. When he finishes that particular job he again inserts that same ticket in the job time recorder and makes a second time imprint. The difference in time between these two imprints indicates the elapsed time involved on that particular 20 job.

One of the objects of my invention is to provide such a system with means for correcting the daily error occasioned by the different rates 25 at which the motor picks up after it has stopped and drifts after it has been cut off.

In certain cost-keeping systems it is desirable to have job time recorders automatically stop operating during the non-working periods, which 30 are usually the lunch and supper periods. This is a practice that has been quite extensively used with minute impulse systems, but has not been made use of with synchronous motor-driven recorders, because the recorders would not operate 35 in synchronism when started and stopped, due to the fact that certain motors will start slower than others and also that certain motors will run longer after the current has been cut off.

As indicated above, one of the objects of the 40 present invention is to provide in such a system means for correcting the daily error occasioned by the specific characteristics as to starting and stopping of the various synchronous motors in such a way that the error does not become 45 cumulative.

When the recorders are arranged to eliminate the non-working periods, the type wheels cover a period of less than twenty-four hours. For instance, many job recorders cover a cycle of 50 twenty-two hours. Therefore, in each day of twenty-four hours the recorder must be idle for two hours. This two-hour period may be divided into three divisions, using one-half hour for lunch, one-half hour for supper and one hour, 55 to be eliminated usually just before the be-

ginning of the working day. Occasionally recorders are arranged for a twenty, twenty-one or a twenty-three hour period.

In accomplishing the desired result, a synchronous motor-driven program instrument and 60 suitable sequence switches are employed to open and close the necessary circuit or circuits required for the control of the recorders. Attached to the type wheel mechanism in each recorder is a contact which is caused to open 65 when the movement of the type wheel mechanism reaches a certain predetermined point in its travel, usually the end of the cycle for which the recorder is built. This feature insures that the recorder will always operate until its cycle 70 is completed and therefore can be started off in synchronism at the beginning of each new cycle.

It is, of course, understood that there will be a very slight error in some recorders, due to the fact that the synchronous motors will not always 75 accelerate at the same rate, but as each recorder must complete its cycle before it will stop, this very small error is corrected each time the recorder reaches the end of its cycle which occurs once each day.

80 In the drawing, in which two forms of my invention are shown,

Figure 1 is a diagrammatic view showing a system as outlined above employing an electromagnet in each secondary apparatus; and 85

Fig. 2 is a diagrammatic view showing a system in which there is no electromagnet in the secondary apparatus.

Referring to the drawing in detail, and first to Fig. 1, the system shown therein comprises 90 a plurality of secondary apparatuses, each secondary apparatus comprising a synchronous motor 1, a cam wheel 2 driven by this synchronous motor, a switch 3 controlled by this cam 2 for cutting off the secondary apparatus at the end of its cycle, and master apparatus including a synchronous motor 4, a pair of cam wheels 5 and 5a driven by this master synchronous motor, a sequence switch 6 controlled by the cam wheel 5 for controlling the stopping and 95 starting of the motor 1 for the non-working periods and a sequence switch 8 controlled by the cam wheel 5a for starting the secondary apparatus after the secondary apparatus has stopped itself at the end of its cycle. In addition to the above apparatus, each secondary apparatus is provided with an electromagnet 10 controlled by the sequence switch 8 and a switch 11 in bridge of the cam-controlled switch circuit 12 for assisting in the starting of the sec- 100 105 110

ondary apparatus after it has been stopped at the end of its cycle.

In use, the cam wheel 5 will be designed so as to stop the secondary apparatus at the beginning of each non-working period and start it at the end of each non-working period. Thus, if there is a non-working period from 12:00 noon to 12:30 P. M., the cam wheel 5 will momentarily energize the electromagnet 13 which will advance the sequence switch 6 a quarter revolution, bringing the high point of the cam wheel 13a of the sequence switch underneath the movable contact 14 and thus interrupting the power circuit to the secondary apparatus.

15 At the end of each non-working period, the cam wheel 5 again momentarily closes the circuit for the electromagnet 13, causing the cam wheel 13a to be given another quarter turn, bringing the low spot of the cam wheel 13a underneath the movable contact 14 and allowing the movable contact to drop down onto the cooperating contact 15. This closes the power circuit to the secondary apparatus, causing the secondary apparatus to start up again at the 20 end of the non-working period. This operation is repeated for each non-working period throughout the day.

As indicated above, in one common system, it is usual to have a non-working period for lunch, 30 a non-working period for supper, and a period of idleness at the end of the daily cycle and just before the beginning of the next day's cycle. This period of idleness between the end of one cycle and the beginning of another varies, but 35 in some systems an idle hour is provided so that each secondary apparatus stops itself an hour before the beginning of the next day's cycle, thus insuring that all of the secondary apparatuses are brought into substantial synchronism 40 once each day and preventing any cumulative error due to starting and stopping. For instance, if the day's cycle begins at 7:00 o'clock, each secondary apparatus will cut itself off from the power circuit at 6:00 o'clock. This automatic cut-off is accomplished by the cam wheel 2 which may be so designed that at 6:00 o'clock by secondary apparatus time the cam wheel will open contacts 3 and 20a, interrupting the power circuit and stopping the motor.

45 50 To start it up again, the master control cam wheel 5a is designed to momentarily close the circuit at the beginning of the new cycle which will energize the electromagnet 16 and cause the sequence switch cam wheel 17 to be turned a quarter revolution. This permits the movable contact 18 to drop down onto the cooperating contact 19, completing the circuit for the secondary electromagnet 10, causing the bridge circuit 20 to be closed and thus starting all the secondary apparatus. This will of course cause all 55 of the secondary cam wheels 2 to start rotating and soon the normal circuits for the secondaries will be established by the closing of the contacts 20a and 3 by the secondary cam wheels 2.

60 65 70 Shortly after these normal circuits have been closed, the master cam wheel 5a may again momentarily complete the circuit for the electromagnet 16, causing a further quarter turn of the sequence switch cam wheel 17 and the consequent opening of the contacts 18 and 19. This leaves the apparatus all set for the day's cycle.

75 Referring now to Fig. 2, which shows a system which does not require an electromagnet in the secondary apparatus, it will be noted that

when the cam wheel 2 allows the contact 20a to disengage the contact 3, it will drop down onto a contact 21 which provides a substitute circuit for the motor 1 controlled by the cam wheel 17 of the sequence switch 8.

80 From this it will be clear that the operation of the apparatus of Fig. 2 is substantially the same as that of Fig. 1. The automatic cut-off at the end of the cycle is accomplished by the cam wheel 2, which at the end of the day's cycle will permit the movable contact 20a to disengage the contact 3 and engage the contact 21 which interrupts the power circuit and stops the motor 1. To start the secondaries up again at the beginning of the next day's cycle, the master control cam wheel 5a will momentarily close the circuit, energizing the electromagnet 16 and causing the sequence switch cam wheel 17 to be turned a quarter revolution. This permits the contact 18 to drop down onto the cooperating contact 19, completing the substitute circuit for the secondary motor 1, thus starting all the secondary apparatus. This will, of course, cause all the secondary cam wheels 2 to start rotating and soon the normal circuits for the secondaries will be established by the closing of the contacts 20a and 3 by the secondary cam wheel 2. Shortly after these normal circuits have been closed, the master cam wheel 5a may again momentarily complete the circuit for the 90 electromagnet 16, causing a further quarter turn of the sequence switch cam wheel 17 and a consequent opening of the contacts 18 and 19.

95 Further modifications will be apparent to those skilled in the art and it is desired, therefore, that the invention be limited only by the prior art and the scope of the appended claims.

Having thus described my invention, what I claim and desire to secure by Letters Patent is:

1. A synchronous motor job time recorder system comprising master apparatus and a plurality of secondary apparatuses, each secondary apparatus comprising a synchronous motor and means controlled by the individual secondary apparatus time for stopping it at the end of its cycle, said master apparatus comprising means controlled by master apparatus time for stopping the secondary apparatus and for starting the secondary apparatus after they have been stopped by the master apparatus, and means 110 controlled by master apparatus time for starting the secondary apparatuses after they have been stopped by the secondary apparatuses themselves at the end of their cycles.

115 120 125 130 135 140 145

2. A synchronous motor job time recorder system comprising master apparatus and a plurality of secondary apparatuses, each secondary apparatus comprising a synchronous motor and means controlled by the individual secondary apparatus time for stopping it at the end of its cycle, said master apparatus comprising means controlled by master apparatus time for stopping the secondary apparatus and for starting the secondary apparatuses after they have been stopped by the master apparatus, and means 130 controlled by master apparatus time for starting the secondary apparatuses after they have been stopped by the secondary apparatuses themselves at the end of their cycles, said master apparatus comprising a time-controlled switch for stopping and starting the motors of the secondary apparatuses.

135 140 145 150

3. A synchronous motor job time recorder system comprising master apparatus and a plurality of secondary apparatuses, each secondary

- apparatus comprising a synchronous motor and means controlled by the individual secondary apparatus time for stopping it at the end of its cycle, said master apparatus comprising means controlled by master apparatus time for stopping the secondary apparatus and for starting the secondary apparatuses after they have been stopped by the master apparatus, and means controlled by master apparatus time for starting the secondary apparatuses after they have been stopped by the secondary apparatuses themselves at the end of their cycles, each secondary apparatus being provided with a switch controlling the circuit for its motor controlled by the movement of said motor.
4. A synchronous motor job time recorder system comprising master apparatus and a plurality of secondary apparatuses, each secondary apparatus comprising a synchronous motor and means controlled by the individual secondary apparatus time for stopping it at the end of its cycle, said master apparatus comprising means controlled by master apparatus time for stopping the secondary apparatus and for starting the secondary apparatuses after they have been stopped by the master apparatus, and means controlled by master apparatus time for starting the secondary apparatuses after they have been stopped by the secondary apparatuses themselves at the end of their cycles, each secondary apparatus being provided with a switch controlling the circuit for its motor controlled by the movement of said motor, and a circuit in bridge of said motor-controlled switch controlled by the master apparatus.
5. In a job time recorder system in which a plurality of synchronous motor time-controlled recorders are periodically stopped for certain predetermined non-working periods by master control apparatus, means for periodically synchronizing said recorders to correct for differences in starting and stopping rates of the synchronous motors.
6. In a job time recorder system, master apparatus, a plurality of synchronous motor controlled recorders, means in said master apparatus for stopping and starting said recorders, and means periodically effective for correcting the deviations in time registered by said recorders due to differences in the accelerating and retarding characteristics of the synchronous motors.
7. In a job time recorder system, master apparatus, a plurality of synchronous motor controlled recorders, means in said master apparatus for stopping said recorders at the beginning of each of a plurality of non-working periods and for starting said recorders at the termination of each of said non-working periods, and means for periodically synchronizing said recorders to correct for differences in the starting and stopping rates of the synchronous motors, said means including means in each recorder for stopping it at a predetermined point in its operation and means in said master apparatus for starting all of said recorders together.
